UNITED STATES PATENT OFFICE.

FREDERICK MANKEY, OF WILLIAMSPORT, PENNSYLVANIA.

DESIGN FOR A PANEL.

SPECIFICATION forming part of Design No. 16,399, dated December 1, 1885.

Application filed July 18, 1885. Serial No. 372,006. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design consists of a central frusto-pyramidal elevation, A, having rounded sides B and surmounted by a flat surfaced rectangular elevation, C. The elevation A is formed with its edges standing diagonally upon the panel, as shown. Disposed around the elevation A, and each having one side parallel to the adjacent side of said elevation are triangular frusto-pyramidal elevations D, having rounded sides, and each surmounted by a flat-surfaced triangular elevation, E. Between the eleva-

tion A and the elevations D are channels or spaces F. The outer contour of the design is rectangular, as shown.

I claim—

The design for a panel, substantially as herein shown and described, consisting in the central frusto-pyramidal elevation A, having rounded sides B and surmounted by a flat-surfaced rectangular elevation C, the triangular elevations D, correspondingly composed, and the intermediate channels, E, the inclined sides 30 of said elevations showing a different grain-marking from that which appears on their flat surfaces.

FREDERICK MANKEY.
